(57) **CLAIM**

We claim the ornamental design for a remote control housing, as shown.

DESCRIPTION

FIG. 1 is a top front isometric view of a remote control housing showing our new design;

FIG. 2 is a front elevation view;

FIG. 3 is a rear elevation view;

FIG. 4 is a right side elevation view;

FIG. 5 is a left side elevation view;

FIG. 6 is a top plan view; and,

FIG. 7 is a bottom plan view.

The broken lines illustrate portions of the remote control housing that form no part of the claimed design.
